Edgar Patent Co.

UNITED STATES PATENT OFFICE.

HUDSON ZALMON LOSEY, OF WHITE PLAINS, NEW YORK.

DRAPERY-SUPPORT.

1,284,726.

Specification of Letters Patent. Patented Nov. 12, 1918.

Application filed March 11, 1918. Serial No. 221,615.

To all whom it may concern:

Be it known that I, HUDSON Z. LOSEY, a citizen of the United States, and residing at White Plains, in the county of West 5 chester and State of New York, have invented certain new and useful Improvements in Drapery-Supports, of which the following is a specification, such as will enable those skilled in the art to which it apper- 10 tains to make and use the same.

This invention relates to drapery supports particularly designed for use in connection with windows whereby curtains, draperies and the like may be suspended from the top 15 portion of a window frame, and the object of the invention is to provide a simple bracket device which is preferably composed of sheet metal and which may be connected with the top portion of the sides of a window frame and with which one or more drapery poles or rods may be detachably 20 connected.

The invention is fully disclosed in the following specification, of which the accompanying drawing forms a part, in which the separate parts of my improvement are designated by suitable reference characters in each of the views, and in which:

Figure 1 is a plan view of one side of a 30 window frame, indicating one of my improved bracket devices connected therewith and indicating the window frame in section;

Fig. 2 a section on the line 2—2 of Fig. 1; 35 Fig. 3 a perspective view of the attaching bracket which I employ; and,

Fig. 4 a perspective view of one end of one of a number of drapery poles or rods which I employ.

40 In Figs. 1 and 2 of the drawing I have indicated at a the upper right hand corner of a window frame and, in the practice of my invention, I preferably secure to the side members a^2 of the frame adjacent to the top member a^3 thereof, a plurality of spaced screws or other headed attaching devices b , one of which is shown in Fig. 2 with which my improved bracket device c may be detachably connected.

50 The bracket device c is preferably composed of sheet metal bent to form an elongated back portion c^2 and an approximately rectangular side portion c^3 which extends at right angles to the back portion c^2 and the top edge of which is folded downwardly as shown at c^4 to reinforce the top part of the

rectangular side portion c^3 . The back c^2 is provided with two spaced apertures c^5 having upwardly directed reduced extensions c^6 . The side portion c^3 is provided with vertically arranged apertures c^7 provided at the top thereof with elongated or enlarged apertures c^8 which are approximately rectangular in form as indicated in Fig. 1 of the drawing. 65

In attaching the bracket device c to the window frame, the screws or other attaching devices b are first secured to the window frame a a predetermined distant apart, after which the bracket device c is placed 70 in position by passing the heads of the attaching devices b through the apertures c^5 and moving said device downwardly as will be readily understood and, as clearly indicated in Fig. 2. 75

I also employ a drapery pole or rod d , one or more of which may be employed, and two of which are shown in Fig. 1, and connected with the end portions of said pole or rod d are elongated head members e formed 80 from sheet metal bent centrally to form said head members e , and the ends e^2 of which are bent outwardly and are connected with the ends of the pole or rod by an inclosing sleeve f , and between the elongated head 85 members and the ends e^2 are neck portions e^3 , and in attaching a pole or rod with the bracket device c the neck portion e^3 and elongated head members e on the ends of said pole or rod are passed downwardly 90 through the apertures c^8 and c^7 , and as clearly indicated in Fig. 1 the neck portions fitting snugly within the apertures e^7 and by reason of the elongated head portions e the pole or rod is held against displacement. 95

It will be understood that my invention is not limited to the number of poles or rods employed in connection with my improved bracket, nor to the particular form and construction of the head portion e on the end 100 of the pole or rod d , and various changes in and modifications of the construction herein shown and described may be made, within the scope of the appended claims, without departing from the spirit of my invention 105 or sacrificing its advantages.

Having fully described my invention, what I claim as new and desire to secure by Letters Patent, is:—

1. A bracket device for the purpose de- 110 scribed, comprising a body portion L-shaped in cross section and consisting of a back

plate member and a side plate member, the back plate member being provided with a plurality of spaced apertures having upwardly directed and reduced extensions and 5 the side plate member being provided at the top thereof with an outwardly and downwardly directed reinforcing portion in the top of which are apertures having reduced extensions which extend downwardly into 10 the side plate member.

2. A bracket device for the purpose described, comprising a body portion L-shaped in cross section and consisting of a back plate member and a side plate member, the 15 back plate member being provided with a plurality of spaced apertures having upwardly directed and reduced extensions and the side plate member being provided at the

top thereof with an outwardly and downwardly directed reinforcing portion in the 20 top of which are apertures having reduced extensions which extend downwardly into the side plate member, and a pole the end portions of which are provided with elongated heads having reduced necks and adapted to be passed downwardly through said apertures into the reduced extensions thereof. 25

In testimony that I claim the foregoing as my invention I have signed my name in presence of the subscribing witnesses this 8th day of March 1918.

HUDSON ZALMON LOSEY.
